[57] CLAIM

The ornamental design for a chair, as shown and described.

DESCRIPTION

FIG. 1 is a top plan view of a chair embodying the claimed ornamental design;

FIG. 2 is a front elevational view of a chair embodying the claimed ornamental design;

FIG. 3 is a side elevational view of a chair embodying the claimed ornamental design;

FIG. 4 is a bottom view of a chair embodying the claimed ornamental design;

FIG. 5 is a rear elevational view of a chair embodying the claimed ornamental design;

FIG. 6 is a perspective view of a chair embodying the claimed ornamental design; and,

FIG. 7 is a perspective view of a chair showing a second embodiment of the design, the only differences being the omission of welting, the non-removable seat cushion and the cushionless backrest.

FIG. 6 and 7 have been shown on an enlarged scale with respect to FIGS. 1 through 5.
